UNITED STATES PATENT OFFICE.

JOHN W. HOWELL, OF NEWARK, NEW JERSEY, ASSIGNOR TO GENERAL ELECTRIC COMPANY, A CORPORATION OF NEW YORK.

INCANDESCENT LAMP.

SPECIFICATION forming part of Letters Patent No. 726,929, dated May 5, 1903.

Application filed April 29, 1901. Serial No. 57,883. (No model.)

To all whom it may concern:

Be it known that I, JOHN W. HOWELL, a citizen of the United States, residing at Newark, county of Essex, State of New Jersey, have 5 invented certain new and useful Improvements in Incandescent Lamps, (Case No. 2,153,) of which the following is a specification.

This invention relates to incandescent electric lamps, and is of particular importance in connection with lamps with treated filaments intended to be operated at about two hundred and twenty volts and upward. There has been great difficulty in producing a lamp 15 of this kind heretofore, for the reason that a filament sufficiently long and thin to be economical could not be successfully handled in the treating and exhausting operations in the manufacture of the lamps.

20 By my invention I am enabled to produce a sixteen-candle power treated filament which may be operated at two hundred and forty volts with an energy consumption of 3.4 watts per candle. To provide a lamp of this kind 25 requires a very thin filament, which on account of its weakness with a length sufficient to cause a high-voltage drop, is distorted in the treating-bottle (a step in its manufacture to render it uniformly conductive) after the

30 vegetable matter of which it is composed has been carbonized. A very thin filament is so weak at the high temperature to which it is brought in the treating-bottle that it is unable to sustain itself. The same trouble occurs 35 in the lamp-bulb during the exhausting operation, and besides this there is a damage to the filament both during the treating process and at a certain stage of the exhausting process from leakage-currents. By means of

40 my invention these difficulties are avoided. I proceed by forming the filament of a plurality of sections, or, in fact, by taking several independent filaments and subjecting them to the treating process, by which they 45 are rendered of uniform conductivity. Thus each section is only a fraction of the entire length and may be treated without danger of sagging. Two of these filaments are mounted in the same bulb and on the same support- 50 ing-stem and connected together in series by a cement joint and attached to a fine-wire

support sealed in the glass of the stem, the outer ends of the conjoined filaments being connected to independent conductors which form the lamp-terminals. It is necessary to 55 successful exhaustion that the three cement joints should be equally heated, otherwise the gases and hydrocarbons will not be sufficiently expelled from all of them, and in order to effect this I reduce the loss of heat 60 in the joint between the adjacent ends of the two filaments by making the support of finer wire than the leading-in wires, thereby bringing the joint to the same temperature as the others by reason of its decreased heat-dissipating capacity. Both filaments being connected to one point add their heat, and the decreased capacity to dispose of the heat raises it to an equality with that at the other joints. In order to drive out the moisture 70 which is trapped in the pores of the joints, I subject the filaments after being mounted on the stem to a heating process before putting the lamps on the pumps. By this procedure damage to the filaments from the high 75 potential during the exhausting and treating processes is avoided and a satisfactory high-voltage lamp is produced.

The several features of novelty will be hereinafter more particularly described and will 80 be definitely indicated in the claims appended to the specification.

In the accompanying drawing, which illustrates my invention, is shown a side elevation of a lamp embodying my improvements. As 85 will be seen, it is composed of a multiple filament formed of two sections connected in series relation, the several parts of which are marked 1 and 2, respectively. The connected ends of the two sections are secured together by a cement joint of the usual character and to a wire 3, sealed into the stem of the lamp. In order to reduce the loss of heat at this joint, the wire 3 is made of smaller cross-section than the other two wires sealed 95 into the glass pillar which supports the filament, the degree of fineness, of course, varying according to the nature of the metal used, and the two connected legs of the filament are joined to the same end of the thin-wire 100 support at the same point, thereby making this joint as hot as those with the leading-in

wires. In order to prevent cross connection or contact of the two sections of the filament under vibration, I anchor them at intermediate points by iron wires 6 7, mounted on 5 the ends of glass posts 8 9, fused fast to the stem which supports the filament. The outer ends of the multiple filament are connected with terminals 4 5, leading through the stem in the usual manner.

10 With a high-voltage lamp of the class to which this invention relates damage is liable to result to the filament from current leakage during exhaustion across the ingoing and outgoing ends of the filament or from arcs or 15 discharges which tend to form at comparatively low voltages at the pressures used in incandescent-lamp exhaustion. Besides this, a filament which is of sufficient tenuity to afford a voltage-drop of two hundred and 20 twenty with sixteen-candle power will sag and become distorted. Both these difficulties are avoided by the construction hereinbefore described, the preliminary expulsion of the moisture and the equality of heating 25 the joints permitting the exhausting operation to be conducted without damage to the filament.

What I claim as new, and desire to secure by Letters Patent of the United States, is—
30 1. A high - voltage incandescent electric lamp having a filament composed of a plurality of independent treated sections, the sections being joined near the stem on the end of a supporting-wire of smaller heat-radiating capacity than the terminals.
35 2. A high - voltage incandescent electric lamp having a filament composed of two in-

dependent treated sections connected near the stem by a joint of smaller heat-radiating capacity than the terminal joints.

40

3. A high - voltage incandescent electric lamp having a filament composed of two independent treated sections connected by a cement joint supported on the stem, and means for insuring equality of heating of the 45 several joints.

4. A high - voltage incandescent electric lamp having a filament composed of two sections each of which is a treated filament, the two connecting at adjacent ends to the same 50 point of a wire of smaller heat-dissipating capacity than the terminals and mounted in the stem, and an anchor for the intermediate points of the several sections.

5. A high - voltage incandescent electric 55 lamp containing two treated filaments connected in series relation and mounted at their junction on a supporting-wire of smaller cross-section than the supports for the terminals.

6. A high-voltage incandescent lamp having 60 two independent treated filaments mounted on the same stem, connected in series relation, the point of connection being mounted on a support of smaller heat-dissipating capacity than the terminals, anchors for intermediate parts of the filaments, and glass supports mounted on the stem for said anchors.

In witness whereroof I have hereunto set my hand this 25th day of April, 1901.

JOHN W. HOWELL.
